CLAIM

(52) U.S. Cl.

The ornamental design for a storage box for bedsheets and duvet covers, as shown and described.

USPC D3/302

DESCRIPTION

(58) Field of Classification Search
USPC D3/201, 273, 274, 276, 279, 290, 295,
D3/302
CPC A47C 17/86; A47B 2210/16
See application file for complete search history.

(56) References Cited

FIG. 1 is a front, top, and left perspective view of a storage box for bedsheets and duvet covers showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is a rear, bottom, and right perspective view thereof. The broken lines shown in the drawings represent portions of the storage box for bedsheets and duvet covers that form no part of the claimed design.
